UNITED STATES PATENT OFFICE

OTTO E. SIDEN, OF BROOKLYN, NEW YORK

GARMENT HANGER AND BRUSH

Application filed May 3, 1930. Serial No. 449,445.

This invention relates to a combined garment hanger and brush particularly adapted for use by travelers inasmuch as it is so constructed that the parts are extensible for use and contractible for non-use in order that when not in use the article may be packed in a valise, or a suit case, and does not then occupy any greater space than an ordinary clothes brush of like dimensions.

10 In carrying out the invention the article made in accordance therewith preferably includes a head member in which there are suitably secured the necessary bristles to make the brush, together with hanger members which are slideable to and form positions for use and non-use and when in the non-use positions are caused to lie in their substantial entirety within the head member. The article also includes suitable clip or clamp devices for engaging and supporting the garment, together with means for suspending the article and the garments carried thereby from a rail, or hook, or other support, as will be hereinafter more particularly described.

In the drawings Figure 1 is a plan of the garment hanger and brush made in accordance with my present invention,

Fig. 2 is a side elevation thereof,

Fig. 3 is an end elevation,

Fig. 4 is a section on line 4—4, Fig. 1,

Fig. 5 is a side elevation showing the parts extended for use, and

Fig. 6 is a perspective view of one of the loop hanger members.

In the form of the invention as illustrated in the drawings the garment hanger and brush made in accordance with this invention is constructed to include a head member. This head member is preferably a two part structure. One of the parts of the head is indicated at 10 and the other part of the head is indicated at 11. The parts of the head are preferably rectangular in plan and coextensive with one another, these parts being secured together by means of suitable screws 12 and 13 passing through the member 11 and into the member 10.

It will be understood, however, that these parts of the head may be connected in any

suitable manner and when desirable the head may be made in one part instead of in a multiplicity of parts. Irrespective of the manner in which the head is made it is fitted with suitable bristles, as indicated at 14, 55 in order to constitute a brush.

The top or upper surface of the head is preferably convex longitudinally, as indicated at 15. In oppositely disposed positions in the sides of the brush head adjacent the ends thereof there are grooves which as illustrated are indicated at 16 and 17 at one end of the brush head and at 18 and 19 at the other end thereof. These grooves are also convex longitudinally and preferably 65 extend in positions parallel with the upper surface of the brush head. Intermediate of the grooves 16 and 18 there is a recess 20 in one side of the brush head and intermediate of the grooves 17 and 19 there is 70 a recess 21 in the opposite side of the brush head. These recesses 20 and 21 also extend longitudinally of the brush head and the upper and lower walls defining the same are also convex so as to be substantially parallel 75 to the top of the brush head. It is to be noted that the grooves 16 and 17 as illustrated extend from the lower or inner portions of the recesses 20 and 21 while the grooves 18 and 19 extend from the upper or 80 outer portions of these recesses, both sets of grooves extending to the ends of the brush head. In the ends of the brush head there are notches 24 and 25, the purpose of which will hereinafter appear.

The article also includes a pair of hanger members preferably in the form of wire loops indicated at 26 and 27. The hanger loop 27 comprises oppositely disposed legs 28 and 29 and an end 30. The extremities of the legs 28 and 29 are inturned to form hooks 31 and 32. The legs 28 and 29 are curved longitudinally to conform to the convexity of the top of the brush body and the grooves 18 and 19 in which the legs 28 and 29 fit and in which they are slideable. The hanger loop 26 is similarly constructed to include legs 33 and 34 curved longitudinally and an end 35 100

which, like the end 30, is straight. The legs 33 and 34 fit within the grooves 17 and 16 in which they are slid able. The extremities of the legs 33 and 34 are in turned to 5 provide hooks, as indicated at 36 and 37.

The width of the recesses 20 and 21 is approximately equal to twice the diameter of the legs of the hanger loop members whereby, as will be understood, when these 10 hanger loop members are in the positions shown in Figs. 1 and 2, for example, the inner portions of the legs thereof lie in super-imposed positions within the recesses and the ends 30 and 35 of the hanger loop 15 members abut against the ends of the brush body.

The recesses 24 and 25 are provided in the ends of the brush head, as hereinbefore described, in order to make it possible to 20 readily grasp the ends of the hanger loop members to withdraw them from the loop body, that is, to extend them to position for use, as shown in Fig. 5. The brush head is provided with sets of stop pins 38 and 39, 25 40 and 41. These stop pins pass through the recessed spaces 20 and 21 and are so placed that the hooks 31 and 32 at the ends of the legs of the hanger loop 27 when extended engage the stop pins 38 and 30 39 to limit the extent of the outward movement of this hanger loop. In like manner the stop pins 40 and 41 are so placed as to be engaged by the hooks 36 and 37 at the extremities of the legs of the loop hanger 35 26 in order to limit the extent of the outward movement thereof. This is clearly illustrated in Fig. 5 of the drawings.

It will now be readily apparent that with the loop hangers thus extended a coat, or 40 vest, or both garments, or a gown, or skirt, or similar garment, may be placed on the article which may be used as a hanger for the same.

The invention also contemplates the use 45 of a set of clips or clamps associated with the brush head in such a manner as to co-operate therewith in engaging and suspending a garment therefrom. The clips are indicated at 42 and 43. These may be made 50 of suitable spring steel, or other like material, and are secured to the brush head by means of screws 44 and 45 associated with the clip 42, and screws 46 and 47 associated with the clip 43. Each of these clips 55 is similarly constructed and as clearly illustrated, for example, in Fig. 3 of the drawings, is provided with a portion adapted to extend across the top of the brush head and to be secured thereto, with portions 48 and 49 which are oppositely curved 60 and extend beyond the brush head, together with in turned portions 50 and 51 which may be suitably curved or otherwise to conform generally with the longitudinally disposed 65 grooves 22 and 23, with the ends of the clip

terminating in in turned portions 52 and 53 which extend appreciably below the outer surface of the member 11 of the brush head. The normal relationship of the side of each clip to the sides of the brush head is such 70 that there is an appreciable space between them and in view of the relatively resilient material of which the clips are made a portion of a garment may be passed between the sides of the clip and the sides of the brush 75 head and be engaged by the clip with sufficient friction to support the garment, for example, as indicated in Fig. 3, the lower end of one leg of a pair of trousers may be placed beneath the clip or clips at one side 80 of the brush and the end of the other trouser leg beneath the clip or clips at the other side of the brush and the trousers thus suspended, or obviously if two pairs of trousers are to be suspended the ends of both legs 85 of each pair are each passed beneath the clips on the same side of the brush head or otherwise. Obviously also skirts, or like garments, may be similarly suspended.

The article also includes a suitable device 90 for suspending the same from a rod, or rail, or hook. As illustrated this includes a hook member 54 at one end of a two part shank, the parts of the shank being indicated at 95 55 and 56. The shank member 56, extending from the hook 54, passes through a screw eye 57 fixed in a centrally disposed position in the base of a longitudinally disposed groove 58 and the top of the brush head. The edges of this groove are preferably parallel, as indicated at 59 and 60. When in its non-use position the hook 54 and the shank members 55 and 56 thereof extend in a position longitudinally of the brush head and the shank members lie within the groove 58 with the outer shank member 55 lying against the face of the edge 59 and these parts may be shifted sufficiently far 100 to cause the hook 54 to frictionally engage the upper surfaces of the brush head with sufficient pressure to normally maintain the hook and its shank in their inoperative positions, as shown in Fig. 1. Obviously also the hook may be moved to the left, as viewed in Fig. 1 and when the screw eye is at the 105 base of the loop between the hook and the shanks, as shown in Fig. 5, to suspend the article and any and all garments suspended thereby from any suitable support such as a rod, or rail, or closet hook.

I claim as my invention:

1. In a combination brush and garment hanger, a brush member having longitudinal grooves on opposite sides thereof, said grooves extending the length of the member, a plurality of resilient clips secured to the brush member and extending over the longitudinally grooved sides thereof, the extending portions of the clips substantially conforming with the corresponding grooves 120 125 130 135 140 145 150 and suitably spaced therefrom so as to receive therebetween a portion of a garment to frictionally retain the same in a suspended position at either side of the brush.

- 5 2. In a combination brush and garment hanger, a brush member having a longitudinal groove in one side and throughout the length thereof, a plurality of clips secured to the brush member and extending over the
10 longitudinally grooved side, said extending clip portions being resilient and shaped to conform to the curvature in the groove at the side of the brush to thereby facilitate the suspension of a garment.

15 Signed by me this 28 day of April, 1930.
OTTO E. SIDEN.
